UNITED STATES PATENT OFFICE.

JOHN H. SCHINDLY, OF LUTHERSBURG, PENNSYLVANIA, ASSIGNOR TO HIMSELF AND CHARLES MARSHALL, OF SAME PLACE.

STUMP-PULLER.

SPECIFICATION forming part of Letters Patent No. 365,204, dated June 21, 1887.

Application filed April 12, 1887. Serial No. 234,518. (No model.)

To all whom it may concern:

Be it known that I, JOHN H. SCHINDLY, of Luthersburg, in the county of Clearfield and State of Pennsylvania, have invented a new and Improved Stump-Puller, of which the following is a full, clear, and exact description.

The object of my invention is to provide a new and improved stump-puller which is simple and durable in construction and very effective in operation.

The invention consists in the construction and arrangement of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of my improvement. Fig. 2 is a side elevation of the same. Fig. 3 is a detail front elevation of the upper part of the posts, and Fig. 4 is a sectional side elevation of the same on the line xx of Fig. 3.

The two front posts, A A, are secured at their lower ends to the base-beam B, and through their upper ends passes a bolt, C, on which is hung a link, D, between the posts A A, and extending through a slot, E', in the rear post, E, and secured to the latter by a wedge, F, passing through the link D, thus uniting the upper ends of the three posts A, A, and E firmly together. On the bolt C, between the posts A A, is also hung a clevis, G, connected by a link, H, to the clevis I, supporting the rear end of a pulling-lever, J, provided with a slot, J', and notches J², for securing the clevis K, connected in the usual manner with the chain or rope placed around the stump to be pulled. The clevis K is held adjustable in the said notches J², so as to increase or diminish the leverage on the pulling-lever J, according

to the resistance offered by the stump to be pulled. The front end of the pulling-lever J is connected in the usual manner with the tackles L L, operated by the rope or chain N, and supported by the chain or links O from the upper end of the rear post, E. The posts A A and E are additionally secured to each other by the braces P.

It will be seen that the manner of uniting the posts at their upper end is very simple and effective, and the clevis K, being adjustable on the pulling-lever J, permits of pulling on the stump according to its resistance offered—that is, with more or less force, as circumstances require.

Having thus described my invention, what I claim as new, and desire to secure by Letters Patent, is—

1. In a stump-puller, the combination, with the front posts and the rear post, of a bolt passing through the upper ends of the said front posts, a link held on the said bolt and passing through a slot in the rear post, and a wedge passing through the said link at the rear edge of the rear post to hold all the posts securely together at their upper ends, substantially as described.

2. In a stump-puller, the three posts A A and E, the bolt C, held in the upper ends of the posts A A, the link D, and the wedge F, passing through the said link D, in combination with the clevis G, held on the said bolt C, the link H, suspended from the said clevis G, the clevis I, connecting the said link H with the rear end of the pulling-lever J, the pulling-lever J, having the slot J' and the notches J², and the clevis K, held in one of the said notches J², substantially as described.

JOHN H. SCHINDLY.
